UNITED STATES PATENT OFFICE.

KONRAD VON KORYTYNSKI, OF VIENNA, AUSTRIA-HUNGARY.

SEWING-MACHINE.

1,081,841.

Specification of Letters Patent. Patented Dec. 16, 1913.

Application filed December 26, 1911. Serial No. 667,603.

To all whom it may concern:

Be it known that I, KONRAD VON KORYTYNSKI, a subject of the Emperor of Austria-Hungary, and residing at 27 Schönbrunnerstrasse, Vienna, V, Austria-Hungary, engineer, have invented certain new and useful Improvements in Sewing-Machines, of which the following is a specification.

10 This invention relates to sewing machines, and has for its object an improved sewing machine, the main feature of which is that the drums, crank disks or other members actuating the looper and the take up move uniformly and with the same angular velocity, and the defects of previous constructions, in which stitches are missed, are eliminated. This improved construction is specially adapted for rapid 15 working since the unfavorable seizing and wearing conditions are avoided which occur in machines with a velocity ratio other than 1:1 between the main spindle and the looper, while at the same time the irregularities in 20 the formation of the stitches and jerks causing the threads to be torn are prevented.

My invention provides an improved driving means for the take up, by which the latter is positively held at rest during the 25 instant at which the uniformly rotating looper engages the thread loop, thereby eliminating the defects of existing constructions, in which stitches are missed by failure of the point of the looper to properly engage the irregularly moving upper thread.

In the accompanying drawings forming a part of this application, and in which similar reference symbols indicate corresponding parts in the several views:—Figure 1 is a vertical section, with parts broken away, illustrating one embodiment of my invention; and Fig. 2 is an enlarged transverse section through the head of the casing shown in Fig. 1.

45 Referring to the drawings, 16 indicates the driving spindle of a sewing machine, which is connected with the spindle 17 of a looper 17^a by a sprocket chain 20 engaging sprocket wheels 18 and 19 of equal diameter 50 on said respective spindles; the wheel 19 preferably running in an oil bath 21.

The drive of the needle rod 22 is effected by means of a crank disk 23 and a connecting rod 24, the crank disk being mounted 55 on the spindle 16. On the needle rod there is fixed a sleeve 25 carrying two rollers 26

and 27. The take up 28, 29 is fulcrumed on a pin 30 and is acted on by a spiral spring lodged in its boss and not shown in the drawing, which spring has the tendency to move upward the long arm 28 of the take up. The head 28 of the take up moves in a circular arc for the purpose of feeding the required length of thread for a stitch to the looper 17^a and then drawing the stitch 60 tight. The swinging movement of the take up is effected by means of a roller 26 cooperating with the short arm 29 of the take up. The roller 27 cooperates with the arm 31 of a lever fulcrumed on a pin 33. The arm 31 is normally pressed by a spring 34 against a pin 35 arranged on the casing of the mechanism. A shiftable stop comprising a double rod member 37, 38 is slidingly mounted in a guide 36, the parts of which 65 rod member are connected by a hinge 39 in such a manner that the upper part 37 can deviate to the left which however it is normally prevented from doing by a spring 40 attached to the guide 36; which spring 70 also produces a certain amount of friction between the lower rod member 38 and the guide 36, whereby the weight of the rods and the pressure of the short arm 29 of the take up are unable to produce downward 75 motion of the rod member. The rod 38 has a lug 41 which is engaged by the arm 32 of a lever comprising arms 31 and 32.

The drive of the take up takes place as follows:—Just before the needle rod attains 80 its lower dead point, its roller 27 comes into contact with the arm 31 and presses it downward so that the lever arm 32 contacts with the lug 41 and pushes upward the rods 37, 38 as long as the downward movement of the needle rod lasts. The upper rod 37 thus comes into contact with the short arm 29 of the take up so that this latter is prevented from following the further downward movement of the roller 26, and is forced 85 upward from its lowest position into the intermediate position shown in full lines in Fig. 2. As the rods 37, 38 owing to the friction caused by the spring 40, do not yield, the take up is stopped in this position until 90 the roller 26 on the next upward motion of the needle rod again comes in contact with the short arm 29 of the take up, whereupon this arm moves upward under the action of the roller 26 until the needle rod reaches its 95 upper dead point. This position of the take up is shown in Fig. 2 in dotted lines. On

the upward movement of the needle rod the roller 26 causes the rod 37 to yield to the left so that this latter does not obstruct the movement of the needle rod. On the next 5 downward motion of the needle rod the roller 26 moves back the rods 37, 38 into their lowermost position. On the further downward movement of the needle rod the short arm 29 of the take up follows the roller 10 26 until the roller 27 again engages the arm 31, when the actions just described are repeated. The looper is so adjusted on the shaft 17 that it engages in the thread loop at the instant the take up is at rest.

15 The automatic lubrication takes places as follows:—The bosses of the chain wheels 18 and 19 are made conical in such a manner that the oil flows from the chain wheels in 20 grooves 42 provided in the parts of the spindles 16 and 17 supported in the bearings 43 and 44. The spindles 16 and 17 are hollow and contain spirals 45 of wire or the like which conduct the oil flowing out of the 25 grooves 42 through radial passages 46 provided in the spindles, through radial passages 47 to the bearings 48 and 49. The oil dripping from these bearings flows back to the oil bath 21 through suitable tubes 50 and

51; the oil thus returned by the tubes 50 and 51 to the oil bath 21 is distributed 30 from said bath by the sprocket wheel 19 and chain 20, so that a perfectly automatic circulation of lubricating oil is obtained. To prevent oil from being thrown off at the bearings 43 and 44 owing to centrifugal 35 force, cups 52 are attached to these latter, the edges of which cups project over the ends of the bosses of the chain wheels 18 and 19.

I claim:—

40 In a sewing machine, the combination of a take-up and looper, drive members therefor, and a shiftable stop independent of said drive members for positively holding said take-up at rest upon engagement of said looper with the thread, and means actuated by said take-up drive member for shifting said stop.

In testimony whereof I have signed my name to this specification in the presence of 50 two subscribing witnesses.

KONRAD VON KORYTYNSKI.
